United States Patent Office.

ISAAC C. NICHOLS, OF UNION, NEW YORK.

Letters Patent No. 67,568, dated August 6, 1867.

IMPROVED BEEF-STEAK PREPARER.

The Schedule referred to in these Letters Patent and making part of the same.

TO ALL WHOM IT MAY CONCERN:

Be it known that I, ISAAC C. NICHOLS, of Union, county of Broome, and State of New York, have invented certain new and useful Improvements in Machines for Preparing or Making Beef-Steak tender; and I do hereby declare that the following is a full, clear, and exact description of the same, reference being had to the annexed drawings, and to the letters of reference marked thereon, in which—

Figure 1 is a side elevation, and

Figure 2 a plan view.

The nature of my invention consists in the employment of three rollers constructed and located in relation to each other as indicated in the drawings; also, in combination therewith, such devices as will be hereinafter described for the purpose of preparing beef-steak by the double operation of rolling and mashing.

A represents the box; b is a sliding apron, and C a sliding guide-board; D E F represent three fluted or corrugated rollers. The roller D should be closely fluted, leaving the elevations almost sharp, while the rollers E F are so fluted as to leave a wide elevation or division between every other groove. d e f are the cog-wheels attached to the rollers bearing the corresponding letters. g is a crank, by which the machine is operated. h is a hinged door or lid.

The operation of my machine is as follow: Motion is given to it by means of the crank, and the beef-steak is fed in from the apron b. As the steak passes in between the rollers D and E it is cut by the sharp elevation on D. The guide-board C directs it between rollers E and F, which completes the operation by mashing it, and leaving it in a very tender condition.

Having thus fully described my invention, what I claim, and desire to secure by Letters Patent, is—

1. The rollers D E F when constructed and placed in the relative position to each other as and for the purpose set forth.

2. In combination with the above, I claim the sliding apron b and sliding guide-board C, as and for the purpose described.

In testimony that I claim the above I set my signature in presence of two witnesses.

ISAAC C. NICHOLS.
